UNITED STATES PATENT OFFICE.

WILLIAM L. MCGOWAN AND LENI LAME, OF GALT, MISSOURI.

INNER-TUBE-PATCHING STAND.

Application filed February 7, 1923. Serial No. 617,648.

To all whom it may concern:

Be it known that we, WILLIAM L. McGOWAN and LENI LAME, citizens of the United States, residing at Galt, in the 5 county of Grundy, State of Missouri, have invented a new and useful Inner-Tube-Patching Stand; and I do hereby declare the following to be a full, clear, and exact 10 description of the invention, such as will enable others skilled in the art to which it appertains to make and use the same.

The invention relates to inner tube patching stands, and has for its object to provide a device of this character comprising a base, an upright carried by said base, a segmentally shaped tire engaging member carried by the upper end of the upright and a foot actuated lever mounted on the guide carried by the upright. The segmentally shaped device is adapted to have an inner tube disposed thereover, which inner tube engages under the foot actuated lever in such a manner, that when the lever is forced downwardly, the tube will be forced into close engagement with the upper surface of the segmentally shaped member and held thereon by the contraction of the tube. The foot actuated lever, when tilted binds on the guide rod.

30 A further object is to provide a tire engaging member, said member comprising spaced bars having their upper edges arcuate shaped, and a U-shaped metallic member having its arms disposed in vertically
35 disposed kerfs in the inner faces of the spaced bars, thereby forming a receptacle for the reception of tire patching material and tools.

With the above and other objects in view
40 the invention resides in the combination and
arrangement of parts as hereinafter set
forth, shown in the drawing, described and
claimed, it being understood that changes
in the precise embodiment of the invention
45 may be made within the scope of what is
claimed without departing from the spirit
of the invention.

In the drawing:—

Figure 1 is a front elevation of the inner tube patching stand showing a tube thereon, and part broken away to better show the structure.

Figure 2 is a top plan view of the stand, part being broken away to better show the structure.

Figure 3 is a detail sectional view through

the foot engaging member and showing a portion of the guide rod.

Figure 4 is a top plan view of the foot lever.

Referring to the drawing, the numeral 1 designates the base of the stand, which base is formed from spaced end bars 2 in parallel relation to each other, which bars are connected together by a centrally disposed bar 3, located at a right angle to the bars 2. Extending upwardly from one side of the centrally disposed bar 3 is a vertically disposed standard 4, which standard has connected thereto at 5, the upper end of a guide rod 6. The lower end of the guide rod 6 is anchored at 7 to the bar 3, and is spaced from the front face of the standard 4. Secured by means of screws 8 to the upper end of the standard 4 is a horizontally disposed tire engaging member 9. The member 9 comprises a horizontally disposed bar 10, which base adjacent its forward and rear end is provided with upwardly extending spaced bars 11, the upper edges 12 of which are substantially arcuate shaped as shown in Figure 1, thereby allowing the inner tube 13 to be easily stretched for flattening the damaged portion 14 thereof into engagement with the arcuate portion 15 of the U-shaped metallic member 16. The arms 17 of the metallic member 16 are vertically disposed and extend into oppositely disposed kerfs 18 in the inner walls of the spaced bars 11, thereby forming a compartment 19, in which compartment patching materials and tools may be placed and stored. The forward bar 11 has hingedly connected thereto at 20 a closure 21, which closes the opening 22 in the bar, and through which opening access may be had to the receptacle or compartment 19.

When it is desired to patch an inner tube 13, the inner tube is placed in the position shown in Figure 1 over the arcuate shaped portion 15 of the U-shaped metallic member 16, and then the tube is passed under the foot actuated lever 23. 100

The foot lever 23 has its rear end provided with an elongated recess 24 for the reception of the guide rod 6, which guide rod extends through a plate 25, secured to the upper side of the lever. It will be seen that when the foot lever 23 is forced downwardly that the inner tube 13 will be stretched and when the foot is removed from

the lever 23, the foot lever will be tilted upwardly at its outer end, therefore the opposite sides of the aperture 26 in the plate 25 will engage frictionally the opposite sides of the guide rod 6, thereby holding the lever 23 in the position to which it may have been moved, and consequently holding the inner tube 13 in stretched condition so that it may be repaired on its upper side at 14. To further insure the upward movement of the outer end of the foot lever 23, a coiled spring 27 is provided, which coiled spring is disposed in a recess 28 of the lever 23 and engages the forward side of the guide rod, therefore it will be seen that the lever will be positively actuated. When it is desired to move the lever 23 downwardly, it is only necessary for the operator to place his foot on the lever 23 and force the same downwardly in substantially a horizontal position, which action will break the jamming action with the rod 6 and cause the lever to move downwardly.

From the above it will be seen that an inner tube patching stand is provided, which is simple in construction, positive in operation, and constructed in such a manner that an inner tube may be securely held thereon while being patched.

The invention having been set forth what is claimed as new and useful is:—

An inner tube patching stand, comprising a base, a vertically disposed standard carried by the base, a guide rod carried by the standard, a vertically movable foot engaging member carried by the guide rod and held at various adjusted positions by frictional engagement with the guide rod, a member carried by the upper end of the standard, said member comprising a base, spaced bars carried by said base and having their upper sides arcuate shaped, a door in the side of one of the bars centrally thereof, a U-shaped member interposed between the bars, the arms of the U-shaped member extending downwardly into kerfs in the inner faces of the bars, thereby forming a receptacle behind the door carried by one of the bars.

In testimony whereof we have signed our names to this specification in the presence of two subscribing witnesses.

WILLIAM L. McGOWAN.
LENI LAME.
